ESCAPEMENT DEVICE

René Philippe Jaccard, Geneva, Switzerland, assignor to Albert Jean Devaud, Geneva, Switzerland

Application April 23, 1945, Serial No. 589,898
In Switzerland April 27, 1944

12 Claims. (Cl. 58—117)

1

This invention relates to escapement mechanisms for time pieces or the like, and more particularly to a novel arrangement which is substantially shockless and noiseless in operation.

Accordingly, a primary object of the invention is to provide an escapement mechanism wherein the shock and frictional losses are reduced to a minimum, said mechanism including an escape wheel and stop and impulse controlling pawls each having pallet means, the stop pawl being pivoted to the frame while the impulse pawl is pivotally carried by an oscillating impulse transmitting lever, said stop and impulse pawls cooperating with the escape wheel to easily and substantially noiselessly permit the same to move without the excess energy and frictional losses heretofore common to escapement mechanisms now in general use.

With the above and other objects in view, which will more readily appear as the nature of the invention is better understood, the same consists in the novel construction, combination, and arrangement of parts hereinafter more fully described, illustrated and claimed.

Preferred and practical embodiments of the invention are shown in the accompanying drawings, in which:

Figure 1 is a side elevation, partly in section illustrating one form of the mechanism.

Figure 2 is a cross section taken on the line A—A of Figure 1.

Figure 3 is a front elevation of a modification of the invention.

Figure 4 is a top plan view, partly in section, of the construction shown in Figure 3.

Figure 5 is a diagrammatic view showing a variation of the invention illustrated in Figure 2.

Figure 6 is a detail perspective view of a further variation of the invention including a pendulum as the regulating means.

Figure 7 is a detail view showing a modification similar to Figure 3.

Figure 8 is a detail perspective view of another modification of the invention utilizing a balance wheel as the regulating means.

Similar reference characters designate corresponding parts throughout the several figures of the drawings.

Referring to the drawings, it may be generally pointed out that Figures 1 to 8 inclusive illustrate, by way of example, and not by way of limitation, two classes of embodiment of the invention. Figures 1, 2, 5, and 6 illustrate the preferred form of the invention wherein the regulating element of the time mechanism is a pendu-

2

lum, while Figures 3, 4, 7, and 8 illustrate a second class wherein the regulating element is a balance wheel subjected to the action of a spring. Thus, the term regulating element or regulating means as used herein includes a pendulum or a spring tensioned balance wheel.

Referring to embodiments of the first class, where the regulating element of the time mechanism is a pendulum, and in particular to Figures 1, 2, 5, and 6, it is pointed out that the escapement mechanism of Figures 2 and 5 has been drawn to a larger scale than in Figure 1, in order to more readily understand the construction and operation involved.

15 A distinctive feature of the invention resides in the provision of a pair of pawls each having pallet means for engaging the teeth of the escape wheel, said pawls being conveniently designated as a stop pawl A and an impulse transmitting pawl B, the former pivotally mounted to a frame part and the latter pivotally carried by the end of an oscillatable drive or impulse lever C which is connected with the regulating means, whereby the impulse of the escape wheel may be periodically and accurately delivered to said regulating means.

In Figures 1 and 2, the pendulum 1 is flexibly suspended by a rod 2 in a conventional manner indicated as 2^a from the part 3^b of a frame 3. An escape wheel 4 is mounted on a shaft 4^a journalled in the frame parts 3 and 3^a and operatively connected to a prime mover (not shown) in the usual manner by a system of gear wheels, only the first two of which, 5 and 6, are shown.

35 Cooperating with said escape wheel is a stop pawl A having the arms 7 and 7^a and pivoted at 8 to the frame part 3^b, said arms terminating in what may be conveniently termed the safety pallet 9^a and the stop pallet 9^b adapted alternatively to cooperate with the teeth of the escape wheel.

40 While both pallets have a "stop" action since pallet 9^b stops the escape wheel when same is moving "forward" in direction f¹ and pallet 9^a stops the escape wheel when the same is pushed "backwards" in the direction opposite to f¹ by the 45 impulse pawl B under the action of the momentum of the pendulum towards the end of the "backstroke" of the impulse transmitting lever, nevertheless, the pallet 9^a is herein described as a safety pallet because it avoids extensive backward movement of the escape wheel under two conditions, first, when the amplitude of the pendulum is larger than necessary as might happen when starting the pendulum by hand, and, second, when manually setting the hands of the 50 time piece in a counterclockwise direction.

Between said escape wheel 4 and said stop pawl A, there is provided an impulse transmitting pawl B having the arms 10 and 10^a. This pawl is pivotally supported at 11 on the end of the shank 12 of the oscillatory lever C whose upper end is carried by shaft 13 which turns in bearings on the frame parts 3^a and 3^b. A spring blade 15 fastened by a clamp 14 to the shaft 13 moves back and forward in synchronism with the lever C and during the forward movement of each complete oscillation, a yoke 16 carried by the blade gives an energy impulse to the pendulum 1 through the rod 2. Owing to the flexibility of the blade 15, the oscillatory movements of the lever C and the pendulum 1, although of the same frequency, may be quite different in their amplitude. It will be noted that both pawls A and B have a somewhat symmetrical shape resembling that of a ship's anchor and for that reason are stated to be of the "anchor type."

Referring to Figure 2, the complete cycle of operation may be described as follows:

The escape wheel 4 urged to move "forward" in the direction of the arrow f¹, by the prime mover (not shown), is held back momentarily by the pallet 9^b of the stop pawl A. Lever C, oscillatable with shaft 13, is shown in the middle position of its back swing in the direction of the arrow f², during which it is driven by the pendulum 1, to which it is operatively connected by clamp 14, spring blade 15 and yoke 16. The lever C carrying the impulse pawl B moves toward the left in Figure 2 and causes cam surface 17^b on the underside of the arm 10 of the pawl B to come in contact with the top surface of cam 18^b on the arms 7 of the stop pawl A which is momentarily at rest.

When the pallet 10^b of the impulse pawl B advances toward the left and rocks about pivot 11 in the direction of arrow f⁷ in Figure 2 and reaches the tooth D¹ of the escape wheel it pushes the same slightly backwards owing to the momentum of the pendulum. At that instant, the pressure exerted by tooth D² of the escape wheel on the stop pallet 9^b of the stop pawl A is relieved, and said stop pawl rocks or falls by gravity in a counter-clockwise direction according to arrow f³. The left arm 7 of the stop pawl A is heavier than the right arm 7^a. This same action may be obtained by other means, such for example as light springs, shown in Figures 3 and 5. As the stop pawl A rocks in the direction of the arrow f³, the safety pallet 9^a locates itself between the teeth D³ and D⁵ and rather close to D³ with large oscillation of the pendulum. Before the lever C reaches its extreme position on the left, tooth D³ of the escape wheel abuts against the safety pallet 9^a on the right arm 7^a of the pawl A, thus preventing excessive backward movement of the escape wheel under either of the conditions heretofore mentioned.

Lever C terminates its back swing and begins a new oscillation forward, that is in the direction of the arrow f⁴, driven as it is by the impulse pawl B which is also itself pushed by the tooth D¹ of the escape wheel. During a fraction of this part of the cycle, the lever C transmits an impulse of mechanical energy to the pendulum 1 and drives it. The oscillation of the lever C in the forward direction continues, and contact is established between cam surface 17^a at the underside of the arm 10^a of the impulse pawl B and the surface of the cam 18^a on the arm 7^a of the stop pawl A. This causes the stop pawl to rock in the direction of arrow f⁵ and stop pallet 9^b of

the arm 7 locates itself in the space between teeth D² and D⁴ of the escape wheel and at the same time the safety pallet 9^a clears the escape wheel. Said escape wheel 4 keeps moving in the direction of the arrow f¹ until it is arrested by stop pallet 9^b acting on tooth D⁴. Thus, stop pallet 9^b has permitted escape of one tooth of the wheel in its direction of continuous movement. The momentum of the pendulum carries the lever C farther to the right and the pallet 10^b of the impulse pawl B abandons tooth D¹ while the cam surface 18^a of the stop pawl A acting on the surface of cam 17^a causes the impulse pawl B to rock in the direction of arrow f⁶. After the pendulum and lever C come to the end of their forward oscillation, the said pendulum then drives the lever C back to the position from which the present cycle began. The impulse cycle from the escape wheel to the pendulum is again completed, and the impulse cycle as well as the return cycle repeat themselves so long as the prime mover (not shown) is exerting sufficient force on the escape wheel.

From the foregoing it will be apparent that there is a complete absence of shocks during the entire cycle, as well as the absence of sliding motion between the power transmitting elements during the time they actually do transmit power thereby resulting in silent operation, great saving of power required from the prime mover, elimination of lubrication difficulties and making other improvements possible in the clocks, counters and the like.

In particular, each of the principal elements of the escapement device, namely, the wheel, the pawls, and their pallets having a simple duty to perform, their shape, and therefore their manufacture is simplified or facilitated owing to enlarged tolerances. For instance, instead of the rather complicated tooth shape common to most escape wheels, mechanisms according to the present invention may use straight flanked teeth. Further, each pawl and its pallets may be freely adjusted independently of one another. An adjustment performed on one pawl has little or no influence on the adjustment of the other. Further, the stiffness and shape of springs 18^c, 18^d, and 22^a may vary within reasonably large tolerances without impairing the performance of the escapement mechanisms as a whole.

It is also pointed out that the amplitude of oscillation of the lever C is determined by the combined action of the pawls A and B with the escape wheel, and that for each complete oscillation of the pendulum, the shaft 13 receives an energy impulse from the escape wheel as the lever moves in the direction of arrow f⁴.

Figure 5 shows a different arrangement of the stop pallet A' and the impulse pallet B'. The operation of cams 18^a and 18^b in connection with the corresponding surfaces of the arms 10 and 10^a of pawl B in Figure 2 is replaced by the action of the light springs 18^c and 18^d on the extension or head 10^a of the shank 12^a of the impulse transmitting lever C' in Figure 5, said action being not necessarily continuous.

Figure 6 illustrates a different form of connection between the oscillating lever and pendulum which may be adapted to either form of embodiment of the elements A and B shown in Figure 2, or A¹ and B¹ shown in Figure 5. Lever 14^a pivoted on clamp 14^b terminates in an offset finger 16^a contacting pendulum 1^b at the location of the clamp 1^a. Coil spring 15^a allows lever 14^a to perform a relative angular movement with respect

to arm 14^b. Oscillation of lever C of Figure 2 or C¹ of Figure 5 may track exactly together with pendulum 1 or 1^b respectively so long as the finger 16^a of lever 18 abuts against clamp 1^a. Under certain circumstances, however, the pendulum may be driven so far to the right of Figure 6 that the oscillating lever could not follow without straining the pawls A-B or A'-B'. In such cases, spring 15^a gives the desired freedom between the pendulum and the oscillating impulse transmitting lever.

As to the second class of devices, wherein the regulating element is a balance wheel, it may be observed that while the balance wheel spring, in its major portion, most usually assumes the shape of a true flat spiral, as in the great majority of watches where it is often referred to as the "hair spring," it may also take the shape of a cylindrical coil as is usually the case in marine chronometers, or it may be a torsion wire, rod, blade, or even a different shape. The term "hair spring" as used herein is intended to designate a spring of any shape whatsoever having the capacity to produce the so-called "restoring force," which, in conjunction with the inertia of the balance wheel, determines the natural frequency of oscillation of said balance wheel.

Referring to Figures 3 and 4, an escape wheel 19 cooperates with a stop pawl A² including the arms 20 and 20^a having pallet means at the ends thereof and an impulse transmitting pawl B² having the arms 21 and 21^a, said pawls A² and B² being arranged and working together in the manner described heretofore in connection with Figure 2. The impulse transmitting pallet B² subjected to the action of spring 22^a is articulated at 22 on the arm 23 of a Z-shaped oscillating lever C² which is pivoted to the framework of the mechanism as indicated at 24. The arm 25 of the oscillating impulse transmitting lever C² carries two rollers 26 which embrace the hair spring 27 of the balance wheel 28 at a point relatively near the fastening 29 which anchors the spring to the frame. The operation of the various elements in Figures 3 and 4 is in principle the same as previously described. The said Z-shaped lever C² performs the same functions as the lever C in Figure 2 and the portion of the spring 27 between elements 28 and 29 replaces the leaf spring 15 of Figure 1.

For each complete oscillation of the balance wheel 28, an energy impulse is transmitted in the forward direction by the rollers 26, through said hair spring 27, to said balance wheel 28.

Figure 7 shows a different form of hair spring anchor. The end of the hair spring remote from the balance wheel, instead of being anchored to the framework at 29 as in Figures 3 and 4 is fastened at 31 to the arm 28^a of the oscillating lever C³ which in turn is subjected to the action of at least one spring means 32 anchored to the frame 33.

Figure 8 is a partial perspective view of a device combining a balance wheel and a hair spring, otherwise known as a torsion pendulum. In this form of embodiment an oscillating lever C⁴ pivotally carrying an impulse pawl B⁴ is itself pivoted at 24^a on the frame and includes a depending arm 23^a adapted to engage with the free end of an auxiliary spring means 27^a whose other end is anchored at 27^b to the pendulum shaft 27^c. This arrangement gives a desirable freedom of motion between the balance wheel 28^a and the oscillating lever C⁴.

From the foregoing, it will be apparent that

all embodiments of the invention include an impulse-transmitting lever or drive member C, C', C³, or C⁴, carrying therewith a pivotally mounted impulse pawl. This is true even in connection with the modification shown in Fig. 6, where the pawl is omitted for the sake of clarity in illustrating the modified form of connection between the oscillating lever and the pendulum.

From the foregoing it will be clear that the object of the invention is not limited to the arrangements shown in Figures 1 to 8 inclusive. In particular, the lever C of Figure 2 could have a quite different form and have its pivots located elsewhere, for instance, on the axis of the balance member and hair spring 27 or its prolongation as is the case for lever C³ in Figure 7.

Furthermore, the present invention is not limited in its application to a mechanically driven time mechanism comprising either a pendulum or a balance wheel, but can as well be applied to any type of time mechanism to be controlled by the present escapement means, utilizing, for instance, a mechanically or electrically driven, or an electromagnetically driven, escapement wheel.

I claim:

1. An escapement mechanism for time pieces and the like, including, a frame, an escape wheel having teeth and mounted for rotation on said frame, driving means for driving said wheel, regulating means for said wheel including a shaft and an oscillatable drive member fixed thereto, and stop pallet means and impulse pallet means for controlling the intermittent movement of the escape wheel, said stop pallet means being pivoted to the frame adjacent the wheel and said impulse pallet means being pivotally carried by and actuating said drive member of the regulating means, and cooperating means respectively on the stop pallet means and impulse pallet means for controlling their relative movements with respect to the successive teeth of the escape wheel.

2. An escapement mechanism for time pieces and the like, including, a frame, an escape wheel having teeth and mounted for rotation on said frame, driving means for said wheel, regulating means for said wheel including a shaft, an impulse lever carried by the shaft of the regulating means for transmitting the effort from the escape wheel to the regulating means, a stop pawl pivoted to the frame and having stop and safety pallets for alternatively engaging the teeth of the escape wheel, an impulse controlling pawl pivotally carried by the impulse transmitting lever and having a pallet for engaging a tooth of the escape wheel while the stop and safety pallets of the stop pawl are out of engagement with the teeth of the escape wheel, whereby, the turning movement of the escape wheel while it is free of the stop and safety pallets is controlled throughout its arc due to the impulse lever transmitting turning effort of the wheel to the regulating means, and whereby the movement of the teeth of the wheel relative to the pallets of the stop pawl are substantially noiseless and shockless, and cooperating means on the stop pawl and impulse controlling pawl for coordinating their relative movements.

3. An escapement mechanism for time pieces and the like, including, a frame, an escape wheel having teeth and mounted for rotation on said frame, driving means for driving said wheel, regulating means for said wheel including a shaft, a stop pawl pivoted to the frame and having pal-

let means for alternatively engaging the teeth of the escape wheel, an oscillable lever for conveying impulses from the wheel to the regulating means, an impulse controlling pawl pivoted to said oscillatable lever and having pallet means, and cooperating means on said stop pawl and impulse controlling pawl for coordinating their relative movements.

4. An escapement mechanism for time pieces, according to claim 3, wherein, the teeth on the escapement wheel have substantially straight and radial working flanks and the pallet means of the stop pawl and impulse controlling pawl are complementary thereto.

5. An escapement mechanism for time pieces, according to claim 3, wherein, the cooperating means on the stop pawl and impulse pawl are inwardly projecting cams on the stop pawl and corresponding cam surfaces on the impulse pawl.

6. An escapement mechanism for time pieces, according to claim 3, wherein, the cooperating means on the stop pawl and impulse pawl are an extension on the impulse pawl below its pivot and spring elements carried by the stop pawl.

7. An escapement mechanism for time pieces or the like, according to claim 3, wherein, the regulating means is a spring and balance wheel, and the oscillating lever is of substantially Z-shape formation and pivoted at one of its angles to the frame while one free end engages said spring and the other free end supports the impulse controlling pawl.

8. An escapement mechanism for time pieces and the like, including, a frame, an escape wheel having teeth, regulating means, a stop pawl rockably pivoted on the frame and having arms angularly disposed with respect to the pivot, the ends of said arms having pallet means for alternately engaging the teeth of the escape wheel, an impulse pawl having pallet means for also engaging the teeth of the escape wheel, said impulse pawl being located between the arms of the stop pawl, an oscillatable impulse transmitting lever having said impulse pawl pivoted at one end and having its opposite end connected with said regulating means, and cooperating means on the stop pawl and impulse pawl for coordinating their relative movements with respect to the escape wheel.

9. An escapement mechanism for time pieces and the like, including, a frame, an escape wheel having teeth, regulating means, a two armed stop pawl pivoted to the frame and having pallet means at the ends of the arms for alternate engagement with the teeth of the escape wheel, a two armed impulse pawl having pallet means for engaging the teeth of the escape wheel, said impulse pawl being located between the arms of the stop pawl, an oscillatable impulse transmitting lever having the impulse pawl pivoted to one end and having its opposite end connected with said regulating means, and cooperating means on the stop pawl and impulse pawl for coordinating their relative movements with respect to the escape wheel.

10. A substantially shockless and noiseless es-

capement for time pieces, including, a frame, an escape wheel having teeth and supported by the frame, regulating means also supported by the frame, an oscillatable impulse transmitting lever having one end connected to said regulating means, impulse pallet means pivotally connected to the other end of said lever, stop pallet means pivoted for rocking movement on the frame, and cooperating means on the impulse pallet means and stop pallet means for coordinating their relative movements with respect to the teeth of the escape wheel, whereby, the turning effort of the wheel is cushioned with respect to the stop pallet means by the impulse transmitting element connected to the regulating means.

11. In a substantially shockless and noiseless escapement for time pieces and the like, a frame, an escape wheel having teeth, regulating means for the wheel an oscillatable lever connected with said regulating means, and a pair of anchor type pallet elements for engaging the teeth of the wheel, one of said pallet elements being pivoted to the frame and the other being pivoted to said oscillatable lever, and cooperating means on the pallet elements for coordinating their relative movements with respect to the teeth of the escapement wheel.

12. An escapement mechanism for time pieces and the like, including, a frame, an escape wheel mounted on said frame and having teeth, regulating means for the wheel, a two-armed stop pawl pivoted to the frame adjacent the wheel and having stop and safety pallets respectively at the end of each arm for alternate engagement with the teeth of the escape wheel, said stop pallet limiting the forward movement of said escape wheel and said safety pallet limiting the backward movement thereof, an oscillatable impulse-transmitting lever pivotally supported at its upper end in the frame and connected to the regulating means, a two-armed impulse pawl pivotally mounted on said lever adjacent the lower end thereof, one arm of said impulse pawl having a pallet on the end thereof for alternately engaging and disengaging the teeth of the escape wheel and both arms having cam portions, and cam means on the arms of the stop pawl for engaging the related cam portions of the impulse pawl for coordinating the relative movements of said pawls with respect to the escape wheel.
